CLAIM

The ornamental design for a brassiere with front and back crossing closure, as shown and described.

DESCRIPTION

FIG. 1 is a front elevational view of a brassiere with front and back crossing closure, showing my new design;

FIG. 2 is a right front perspective view thereof, with the left front perspective being a mirror image; and,

FIG. 3 is a back elevational view thereof.

The broken lines shown in the drawings are for illustrative purposes only and form no part of the claimed design.
